CLAIM

The ornamental design for a seal with covered vent, as shown and described.

DESCRIPTION

FIG. 1 is a top perspective view of a seal with covered vent showing my new design;
 FIG. 2 is a fragmentary top perspective view thereof with the vent cover exploded;
 FIG. 3 is a top plan view thereof;
 FIG. 4 is a side elevational view thereof, the opposite side being a mirror image;
 FIG. 5 is a front elevational view thereof;
 FIG. 6 is a bottom plan view thereof;
 FIG. 7 is a rear elevational view thereof; and,
 FIG. 8 is an enlarged cross-sectional view on line 8—8 in FIG. 3.

FIG. 1

FIG. 2

FIG. 3

FIG. 4

FIG. 5

FIG. 6

FIG. 7

FIG. 8
